UNITED STATES PATENT OFFICE.

CHARLES WALTON, OF WOODBURY, NEW JERSEY.

RAILWAY-RAIL FASTENER.

No. 834,435.

Specification of Letters Patent. Patented April 14, 1908.

Application filed August 24, 1907. Serial No. 390,069.

To all whom it may concern:

Be it known that I, CHARLES WALTON, a citizen of the United States, residing at Woodbury, in the county of Gloucester and 5 State of New Jersey, have invented a new and useful Railway-Rail Fastener, of which the following is a specification.

This invention relates to concrete cross ties for railways and more particularly to 10 means for fastening the rails in position on the cross ties.

The object of the invention is to provide a concrete cross tie having tubular members embedded therein and adapted to receive 15 the spikes or other fastening devices, there being a wedge disposed at the base of each tubular member for deflecting the bifurcated end of the spike laterally in engagement with the walls of said member thereby to lock the 20 spike against accidental displacement.

A further object is to form the tubular members with spaced cleaning orifices disposed one on each side of the wedge and communicating with the interior of said member 25 so that any deposits of dirt, cement, or other foreign matter entering the tubular member through the upper end thereof may be readily removed prior to introducing the fastening devices or spikes.

30 A still further object of the invention is generally to improve this class of devices so as to increase their utility, durability and efficiency.

Further objects and advantages will appear in the following description, it being understood that various changes in form, proportions and minor details of construction may be resorted to within the scope of the appended claims.

40 In the accompanying drawings forming a part of this specification: Figure 1 is a perspective view of a cross tie constructed in accordance with my invention. Fig. 2 is a transverse sectional view. Fig. 3 is a longitudinal sectional view. Fig. 4 is a perspective view of one of the spikes or fastening devices detached. Fig. 5 is a similar view of one of the tubular members detached.

Similar numerals of reference indicate corresponding parts in all of the figures of the drawings.

The improved device forming the subject matter of the present invention includes a cross tie 5 formed of concrete, cement or 55 other plastic material and having its opposite ends reinforced and strengthened by the pro-

tection of spaced circumferential bands 6 and 7.

Embedded in the concrete forming the body of the tie are a plurality of tubular members 8 preferably angular in cross section, as 60 shown, and having their lower ends deflected laterally to form a conical portion 9. The wall of each conical portion 9 is provided with an annular flange 10 which is preferably countersunk in the lower face of the cross tie. 65 The upper reduced end of each tubular member is also provided with a flange 11 preferably disposed beneath the adjacent reinforcing band, as shown, one side of the flange 11 being cut away to form a square shoulder 12 70 adapted to bear against the flange of the adjacent rail 13 so as to locate the rail on the cross tie and assist in preventing lateral displacement of the same.

Disposed within the flared or conical portion of each tubular member is a wedge shaped block 14 the side walls of which are spaced from the adjacent interior walls of the conical portion 9 thereby to form diverging passages 15 adapted to receive the legs 80 17 of the spike or fastening device 18. The spike 18 is provided with any approved form of driving head 19, while the opposite end of the spike is split longitudinally at 20 to form the legs 17, there being openings 17' formed 85 in the reinforcing bands and registering with the openings in the upper ends of the tubular members to permit the passage of the spikes, as shown. The terminal portions of the legs 17 are inclined toward the slot 20 to 90 form inclined faces 22 which conform to the apex of the reduced end of the wedge 14 and thus assist in guiding the legs 17 within the passages 15 when the spike is driven home with a maul or other suitable tool. 95

Formed in the base of the tubular member on each side of the wedge shaped block 14 are cleaning orifices 23 which communicate with the passages 15 so that any deposits of dirt, gravel or other foreign matter entering 100 the upper end of the tubular member when laying the cross ties on the road bed may be readily removed through the orifices 23 prior to introducing the spikes 18.

The flange 10 of each tubular member is 105 anchored to the cross tie by bolts or similar fastening devices 24, while the adjacent reinforcing band of the cross tie bears against the bottom of said tubular member, as best shown in Figs. 2 and 3 of the drawing.

In fastening the rails to the cross ties, said rails are positioned on the opposite ends of

- the cross ties with the flanges of the rails bearing against the shoulders 12 after which the spikes 18 are introduced in the tubular members and driven home with a maul in the usual manner. As the spikes are forced downwardly within the tubular member the pointed terminal of the wedge 14 will enter the slot 20 in the adjacent spike so that a further downward movement imparted to the spike will deflect the legs 17 transversely of the cross tie in engagement with the inclined walls of the tubular member 9 thus securely locking the spikes against accidental displacement.
- 15 It will of course be understood that the concrete forming the body of the tie may be reinforced by one or more longitudinal cores and that any one of the fastening devices may be employed for securing the rails in 20 position on the cross ties.
- From the foregoing description it will be seen that there is provided an extremely simple, inexpensive and efficient device admirably adapted for the attainment of the 25 ends in view.
- Having thus described the invention what is claimed is:
1. A cross tie including a concrete body portion having its opposite ends provided with reinforcing bands, tubular members embedded in the concrete at said bands and each provided with oppositely disposed flanges, a wedge disposed within each tubular member at the bottom thereof and 30 spikes piercing the reinforcing bands and the adjacent flanges of the tubular members and having their lower ends bifurcated and adapted to engage the wedges for forcing the bifurcated ends of the spikes into engagement with the adjacent walls of the tubular members.
  2. A cross tie including a concrete body portion, a tubular member embedded in the concrete and having its upper end provided 45 with an anchoring flange and its lower end flared laterally and provided with a similar flange, a wedge disposed within the flared portion of the tubular member and spaced from the walls of said tubular member to 50 form converging passages, reinforcing bands surrounding the cross tie at said flanges, and a spike piercing the reinforcing band and the adjacent flange and having its lower end bifurcated and adapted to engage the apex of the wedge for deflecting the bifurcated end of the spike into engagement with the walls of the converging passages.
  3. A cross tie including a concrete body portion, spaced reinforcing bands secured to the opposite ends of the body portion, tubular members embedded in the body portion and each having one end thereof provided with a flange having one side thereof cut away to form a stop shoulder, the opposite end of the tubular member being flared laterally and provided with an annular flange engaging the cross tie beneath the adjacent reinforcing band, wedges disposed within the flared portions of the tubular members and forming converging passages, and spikes 70 having their lower ends bifurcated and adapted to engage the wedges for directing the bifurcated ends of the spikes laterally into engagement with the walls of the converging passages.
  4. A cross tie including a concrete body portion, a tubular member embedded in the body portion and having one end thereof provided with a flange engaging the upper surface of the cross tie, a flange formed on 80 the lower end of the tubular member and engaging the base of the cross tie, the walls of the tubular member at the lower flange being flared laterally, a wedge disposed within the flared portion of the tubular member and forming converging passages, there being cleaning orifices formed in the base of the tubular member and communicating with said passages, and a spike having its lower end split longitudinally to form bendable 85 arms, the terminals of which are inclined towards the split portion of the spike and adapted to engage the apex of the wedge for deflecting said arms in engagement with the walls of the converging passages.
- In testimony that I claim the foregoing as my own, I have hereto affixed my signature in the presence of two witnesses.
- CHARLES WALTON.
